INTERNAL COMBUSTION ENGINE

Franz Lang, Munich, Germany, assignor to
Lanova Aktiengesellschaft, Vaduz, Liechten-
steinApplication May 11, 1932, Serial No. 610,628
In Germany June 10, 1931

5 Claims. (Cl. 123—32)

My invention relates to internal combustion engines and has particular reference to that class of engines in which a volume of air in the combustion chamber is compressed to a degree sufficient to raise its temperature above the ignition point of the fuel, as in the Diesel engine, and in which air is packed in a reservoir chamber during the compression stroke and issues as expansion takes place.

10 It is an object of my invention to improve an engine of the class set out above, with a view to effecting the aforesaid mingling under the most favorable conditions.

To this end I provide a combustion chamber at 15 the cylinder head, with an injection nozzle and the reservoir chamber at opposite sides of the combustion chamber, and with walls extending from the nozzle in opposite directions and toward the reservoir chamber.

20 In the accompanying drawing various arrangements of internal combustion engines embodying my invention are illustrated by way of example.

In the drawing

Fig. 1 is an axial section of the cylinder head and cylinder of an internal combustion engine embodying my invention.

Fig. 2 is a section on the line I—I in Fig. 1.

Fig. 3 is a section of the cylinder head and cylinder of an engine embodying my invention 30 and provided with two nozzles and two reservoir chambers, taken on the axis of one of the nozzles and the reservoir chamber opposite it, and

Fig. 4 is a section on the line II—II in Fig. 3.

Referring now to the drawing, in all figures 1 is the piston, 2 the cylinder, 3 the cylinder head, 4 the combustion room over the piston 1, 5 the combustion chamber, 6 and 7 are the valves in the outer wall of the combustion chamber 5, 8 is the injection nozzle, and 9 is the reservoir or air storage chamber. In Figs. 3 and 4 where the nozzle and the reservoir chamber are duplicated, these parts have been marked 81 and 91, and 82 and 92, respectively.

The principle underlying all the various types which will now be described in detail, is that the jet of fuel from the nozzle and the flow of air from the air storage or reservoir chamber should move in opposite directions so that the air encounters the fuel and hurls it back against the 50 wall of the combustion chamber which receives the nozzle. This effects a very intimate mingling of the air and the fuel, and the mixture which strikes the wall of the combustion chamber at the nozzle side is split up and divided into two 55 flows which perform circular or whirling move-

ments, re-unite near the wall at the reservoir chamber side and are finally deflected into the cylinder.

The rotary or whirling movement of the mixture causes very intimate mingling of fuel and air. 60 The nozzle remains comparatively cool while the fuel is heated before combustion, and all this results in the gradual ignition, and atomized oil only gets to the cylinder.

Referring now particularly to Figs. 1 and 2, the combustion chamber 5 is smaller than the combustion room 4 of the cylinder so that the combustion chamber may be said to be "stepped" with respect to the combustion room 4.

The reservoir or air storage chamber 9 may be 70 cast integral with the cylinder head 3 and connected with the combustion chamber 5 by the passage 13.

10, 11 are two hollow and substantially cylindrical ribs or projections which project from the 75 piston head into the combustion chamber 5. The inner sides of the ribs are flattened to let pass the jet from the nozzle 8 and the return flow from the passage 13.

Compressed air is forced into the reservoir or 80 air storage chamber 9 through its opening 13 and the jet from the nozzle 8 flows in the same direction, during the compression stroke of the piston and ensuing injection of fuel. When ignition and expansion occur, the contents of the reservoir chamber 9 flows toward the combustion chamber while the jet of fuel still issues from the nozzle 8, so that now the air and the jet of injected fuel flow in opposite directions and whirling movement is imparted to the mixture 85 in the two substantially circular portions of the combustion chamber.

The complete atomization of the oil which results from the favorable conditions in the combustion chamber absolutely prevents access of 90 unatomized oil to the cylinder and the piston.

It is important that the outer wall of the combustion chamber 5 should be flat, that is, without projections which might interfere with the regular flow therein. The only projections from the inner face of the wall are the valve bodies 6 and 7 but obviously the valves might be flat.

It is not necessary that the nozzle 8 and the reservoir 9 should be arranged in axially aligned relation but is advantageous that the axes of the 100 two elements include an obtuse angle.

The outer wall of the combustion chamber 5 rises from the nozzle 8 toward the reservoir chamber 9 so that the flat roof of this chamber is inclined upward away from the nozzle 8, and the 105 110

upper surfaces of projections 10 and 11 are inclined similarly to this roof so as to be parallel therewith, as clearly shown in Fig. 1. In this manner the fuel injected from the nozzle encounters gradually increasing sections of the combustion chamber as it approaches the reservoir chamber 9, which facilitates the admixture of fresh air as the mixture is whirled about.

It will appear that by the ribs or projections 10, 11 a positive and regular guiding of the flows in a circular path is effected.

Referring now to Figs. 3 and 4, the nozzles and reservoir chambers are arranged in pairs at opposite sides of the combustion chamber 5, which 15 is similar to that shown in Figs. 1, 2 i. e., has the shape in plan of the numeral 8.

It is not necessary that the nozzles and reservoir chambers be arranged as in Figs. 1 to 3, inclusive. As will appear from Fig. 4 the nozzles 20 and reservoir chambers may be disposed adjacent the ends of the combustion chamber. Obviously, a similar arrangement might be provided for the single pairs of nozzles and reservoir chambers, and it is understood that I am not limited to any 25 particular arrangement of axes. In the example illustrated in Fig. 4 the axes of the nozzles and reservoir chambers are secants of the circles making up the combustion chamber, and at right angles to the line which connects the centres of 30 the two circles. Obviously, they might be tangents, and arranged at any other angle to the line if secants or tangents. A further nozzle 83 and reservoir chamber 93 may be arranged in a central position between the nozzles and chambers at the sides.

The restricted openings 13 of the reservoir chambers open into large curved passages 14, 15. The curving is favorable because it serves for intercepting the fuel as well as for guiding the 40 flow of air from the reservoir chamber.

Various modifications may be made in my invention without departing from its gist. The shape of the combustion chamber should be non-circular but may be varied in many ways, for 45 instance, be a semi-loop, a pointed oval, a form resembling kidneys, and so on.

I claim:

1. In an injection engine, a cylinder and a piston operating therein, a combustion chamber 50 overlying and opening into the cylinder, an air storage chamber opening into the combustion chamber at one side thereof, and an injection nozzle opening into the combustion chamber at the other side thereof, the piston being provided 55 with a projection extending into the combustion chamber and defining with the surrounding wall thereof a substantially annular passage, when the piston is in approximately upper dead center position, the roof of the combustion chamber 60 being flat and inclined upward away from the nozzle and the upper surface of said projection being parallel to said roof.

2. In an injection engine, a cylinder and a piston operating therein, a combustion chamber 65

overlying and opening into the cylinder, an air storage chamber opening into the combustion chamber at one side thereof, and an injection nozzle opening into the combustion chamber at the other side thereof, the piston being provided with a projection extending into the combustion chamber and defining with the surrounding wall thereof of a substantially annular passage, when the piston is in approximately upper dead center position.

3. In an injection engine, a cylinder and a piston operating therein, a combustion chamber of approximately figure 8 shape in plan overlying and opening into the cylinder, projections on the piston and extending into the end portions of the combustion chamber in spaced relation to the surrounding wall of the latter, when the piston is in approximately upper dead center position, said projections being spaced apart to provide a passage therebetween, an injection nozzle having an opening into the combustion chamber at one side thereof disposed to inject fuel into the passage, and an air storage chamber having an opening into the combustion chamber at the opposite side thereof disposed to eject the contents of said storage chamber into said passage.

4. In an injection engine, a cylinder and a piston operating therein, a combustion chamber of approximately figure 8 shape in plan overlying and opening into the cylinder, projections on the piston and extending into the end portions of the combustion chamber in spaced relation to the surrounding wall of the latter, when the piston is in approximately upper dead center position, said projections being spaced apart to provide a passage therebetween extending transversely of the chamber at the constriction thereof, an injection nozzle having an opening into the combustion chamber at one side thereof disposed to inject fuel into the passage, and an air storage chamber having an opening into the combustion chamber at the opposite side thereof disposed to eject the contents of said storage chamber into said passage.

5. In an injection engine, a cylinder and a piston operating therein, a combustion chamber of approximately figure 8 shape in plan overlying and opening into the cylinder, substantially cylindrical projections on the piston and extending into the end portions of the combustion chamber in spaced relation to the surrounding wall of the latter, when the piston is in approximately upper dead center position, said projections having their inner sides flattened and spaced apart and defining a passage therebetween extending transversely of the combustion chamber at the constriction thereof, an injection nozzle having an opening into the combustion chamber at one side thereof disposed to inject fuel into the passage, and an air storage chamber having an opening into the combustion chamber at the opposite side thereof disposed to eject the contents of said storage chamber into said passage.

FRANZ LANG.
